DESIGN FOR A TEXTILE FABRIC

Frederick F. Berlinger, New York, N. Y.

Application January 26, 1939, Serial No. 82,611

Term of patent 3½ years

To all whom it may concern:

Be it known that I, Frederick F. Berlinger, a citizen of the United States, residing in the city of New York, in the county of New York and State of New York, have invented a new, original, and ornamental Design for a Textile Fabric, of which the following is a specification, reference being had to the accompanying drawing, forming part thereof.

The figure is a plan view of a textile fabric, showing my new design.

I claim:

The ornamental design for a textile fabric, substantially as shown.

FREDERICK F. BERLINGER.
